(57) **CLAIM**

We claim the ornamental design for a network device bezel.

DESCRIPTION

FIG. 1 is perspective view of a network device bezel. The broken lines representing the network device housing and instrumentation cut outs are for illustrative purposes and form no part of the claimed design.

FIG. 2 is a front view of the network device bezel.

FIG. 3 is top view of the network device bezel which is a mirror image of the bottom view.

FIG. 4 is a left side view of the network device bezel; and, FIG. 5 is a right side view of the network device bezel.
